UNITED STATES PATENT OFFICE

ARTHUR M. BAUER, OF AKRON, OHIO.

RAIL-JOINT.

1,104,241.

Specification of Letters Patent.

Patented July 21, 1914.

Application filed June 24, 1913. Serial No. 775,514.

To all whom it may concern:

Be it known that I, ARTHUR M. BAUER, a citizen of the United States, residing at Akron, in the county of Summit and State 5 of Ohio, have invented certain new and useful Improvements in Rail-Joints; and I do hereby declare the following to be a full, clear, and exact description of the invention, such as will enable others skilled in 10 the art to which it appertains to make and use the same.

This invention relates to new and useful improvements in rail joints, and has for its object to provide a device of the above character which is adapted to be applied to rails without the necessity of using the usual fish plates; and also eliminating the use of more than one bolt.

Another object of my device is to provide 20 a device which will take the place of a rail chair and also act as a fish plate.

A still further object of my invention is to provide a rail joint chair which will materially assist in forming a tight joint between the ends of rails.

With the above and other objects in view, I will now proceed to describe my invention in the following specification and accompanying drawings, in which,

50 Figure 1 is a side elevation of my improved rail joint as it would appear in place on the rail; Fig. 2 is a bottom plan view of the same; Fig. 3 is a sectional view taken on line 3—3 of Fig. 4; Fig. 4 is a transverse sectional view taken on line 3—3 of Fig. 1; and Fig. 5 is a transverse sectional view taken on line 5—5 of Fig. 2.

Referring to the drawings by characters of reference, 1 indicates the end of a rail 40 which is adapted to abut the end of the adjacent rail 2. The rail 1 is provided adjacent its ends with longitudinal slots 3 which are adapted to receive the lugs formed on the fish plate. The rail 2 is provided adjacent 45 its ends with slots 4, similar to those previously described, which are also adapted to receive lugs formed on the plate.

55 My improved joint, indicated generally at 5, is preferably composed of the two plates 6 and 7. The plate 6 is preferably composed of the web engaging portions 8, which are provided with a lug 9 adapted to be received in the slot 3, previously described. The plate 7 is preferably provided with the 55 extension 10, which passes beneath the rail and is adapted to form a seat for the joint.

The portion 10 is tapered, as clearly illustrated at 11, and provided at its outer extremity with a projection 12, the use of which will be more fully hereinafter described. A depending ear 13 is formed integral with the plate 10 and is provided with an aperture, through which a bolt 14 is adapted to pass.

The plate 6 is extended, as clearly illustrated at 15, beneath the rail and is bifurcated to receive the portion 10 of the plate 7, thus forming the underlying portions 16 and 17, upon which the ends of the rails 1 and 2 are adapted to rest. An ear 18 is provided with the lateral extremities of these underlying portions and is adapted to bridge across between the two, whereby a space between the ear and the plate 6 is provided for the reception of a tongue 12, formed on the seat 10. This ear is provided with a central aperture which is adapted to receive the opposite end of the bolt 14, by means of which the whole is clamped firmly in place.

When it is desired to make use of my improved joint chair in connection with electric signaling systems it is obvious that I may insulate the rails from each other by interposing fiber or other suitable insulating material between the rails and the chair as clearly illustrated in the figures and indicated by the numeral 19.

In operation when it is desired to make use of my improved rail joint, the rail is laid in its desired position, the portion 10 of the plate 6 is then slipped beneath the rail, and the lug 9 formed on the web engaging portion 8 passes into the slot 3 formed in the end of the rail. The coacting plate 7 is 90 then inserted and the tongue 12 passes into the recess beneath the depending ear 18 formed on the plate 6. Thus it will be seen that the apertures in the ears 13 and 18 will be brought into direct alignment, thus permitting the bolt 14 to be inserted. Upon tightening the nut at the end of the bolt the device will be clamped firmly to the rail and thereby prevent accidental removal. The only operation necessary in removing 105 this joint chair from the rails is the loosening of the nut carried by the bolt 14, and the removal of said bolt.

While in the foregoing I have shown and described the preferred embodiment of my 110 invention, I wish it to be understood that I may change the specific arrangements of

parts without in any way departing from the spirit and scope of my invention.

Having thus fully described my invention, what is claimed is:

1. A rail joint chair comprising a pair of plates, upstanding portions formed integral with said plates, lugs formed on the upstanding portions, a bifurcated underlying portion formed on one of said plates, a tongue formed on the other of said plates and adapted to extend into the bifurcation in the first mentioned underlying portion, an ear formed on the tongue near the point where it joins the plate, a second ear formed integral with the bifurcated underlying portion immediately adjacent the point where it joins the plate, said second ear bridging the bifurcation and forming an aperture, each of said ears having an aperture therein adapted to align with the apertured ear, and a bolt adapted to extend through the apertures in the ears to hold the whole together when the device is in use.
2. In a joint chair a pair of plates, upstanding members formed on the plates, said upstanding members being adapted to lie

immediately adjacent the web of a railroad rail and abut the head of said rail, thereby bracing the same, an underlying portion formed on one of said plates, said underlying portion being provided with a centrally located tapered bifurcation extending transversely thereof, a second plate, a tongue formed integral with the second mentioned plate and adapted to extend into the bifurcation in the underlying portion of the first mentioned plate, an ear formed on the tongue near the point where the tongue joins the plate, a second ear formed integral with the underlying portion and bridging the bifurcation, each of said ears having an aperture therein, said apertures being adapted to align when the device is in use, and a bolt adapted to extend through the apertures to firmly clamp the whole in position on the end of railroad rails.

In testimony whereof I affix my signature in presence of two witnesses.

ARTHUR M. BAUER.
